UNITED STATES PATENT OFFICE.

BENNETT T. HOSHALL, OF SHAMBURG, MARYLAND.

FENCE.

SPECIFICATION forming part of Letters Patent No. 595,173, dated December 7, 1897.

Application filed April 28, 1897. Serial No. 633,467. (No model.)

To all whom it may concern:

Be it known that I, BENNETT T. HOSHALL, residing at Shamburg, in the county of Baltimore and State of Maryland, have invented 5 a new and useful Improvement in Fences, of which the following is a specification.

My invention is an improvement in fences; and it consists in certain novel constructions and combinations of parts, as will be herein- 10 after described, and pointed out in the claim.

In the drawings, Figure 1 is a side view of a section of fence constructed according to 15 my invention. Fig. 2 is a detail view illustrating the wiring at one of the end posts. Fig. 3 is a detail view illustrating the wiring of one of the intermediate posts, and Figs. 4 and 5 show somewhat different constructions by which the loops for securing the rails to 20 the posts are interlocked.

My fence is shown as composed of the posts A, the rails B, the riders C, and the stakes D, together with the wire locks by which the 25 said parts are held together in the manner more fully described hereinafter.

It will be understood that the fence may be adapted to turn hogs, &c., by using four, 30 five, six, or seven rails, as necessary, or for horses and cattle a suitable number of rails may be employed, the number of rails being 35 varied to suit the particular purposes for which the fence is designed.

The posts are sunk in the ground and the rails are lapped thereagainst and secured by 40 means of wire locks. On the end posts the locks E are single loops passed around the post and diagonally across and around the 45 ends of the rails, holding such rails firmly to the post. In this construction the several locks may be clamped to the posts by means 45 of nails or staples, or, if desired, openings may be formed through the posts for the passage of the said loops to prevent them from slipping down. On the intermediate posts such expedients are only necessary in connection 50 with the lower loops, the ends of the rails above being all supported from said lower loop, as will be understood from Fig. 3. The stakes are crossed above the top rail and receive the riders, such riders being clamped 55 in place and the stakes being held at their crossing to the top loop of the post by means

of a wire lock F, passed through the top post-loop, thence around both stakes below the rider and around the rider, serving to hold the stakes and rider firmly together and to 55 the post.

In practice I extend the stakes at their upper ends in order that their lower ends, which are driven in the ground, may, when rotted off, be driven farther in, the stakes slipping 60 through the wire lock F without affecting the leverage and tying of said stakes to the posts, as desired. In this connection it may be stated that the stakes are held together a short distance above the ground by means of 65 stays G, which embrace the stakes and are interlocked with some one of the rail-securing loops which encircle the post. It is manifest that this may be effected by passing one or both lengths of the stay G through such 70 loop, and I desire it understood that the interlocking may be effected with any one of the loops on the post, the stay being set higher or lower, as may be desired. These stays are held to their respective stakes, it may be, by 75 notching the stakes and seating the stays in said notches, as shown, or staples or nails or other securing means may be used for such purpose. This is important, as by it the stakes when driven farther into the ground 80 tend to carry the posts down with them, and so tighten up the entire panel of the fence.

At the intermediate posts the rails are lapped thereagainst one above the other and are secured thereto in pairs, the wire locks for 85 such purpose being passed around the post at h, passing over each of such rails near their extremities at h', thence under the other rails of the pair at h'', and secured as best shown in Fig. 3. These several locks H are inter- 90 locked by one loop being passed through the other, as shown in Fig. 3, so the entire chain of loops from top to bottom of the posts is stayed firmly together, holding the several rails in contact with the post and in connec- 95 tion with each other, as is desired.

In Figs. 4 and 5 I show a somewhat different construction of loop. In Fig. 4 the rails are lapped upon each other at their ends, such 100 ends being plain, while in Fig. 5 the ends of the rails are mortised and matched together at I. In these constructions the wire ties J

- are looped around the post, one loop being passed first around the post and then along the outer sides of the rails it secures, the next loop J being passed around the post and thence through the first loop and along the outer sides of the rails it secures, and the succeeding loops are similarly disposed, the end loop being tied to the post as shown at J' or in other suitable manner, as may be desired.
- 10 It will be understood that the center posts and stakes are designed to be sledged into the ground; also, that the manner of leveraging all rails and stakes and riders on the fence is such that the cross-stake can be driven down without loosening any wires or disturbing the fence in any particular, which permits the ready repair of the fence when the stakes are rotted off in the ground, such operation simply requiring the sledging of the stakes to set

them deeper in the ground, as will be readily understood.

Where desired, the fence may be used without the stakes by employing the double loops shown in Figs. 4 and 5.

Having thus described my invention, what I claim, and desire to secure by Letters Patent, is—

In a fence the combination of the post, the rails of the adjacent panels lapping at their ends against said post, and the wire ties passing over each of such rails near their extremities, thence under the other rail of the pair and having a portion passed around the post, substantially as described.

BENNETT T. HOSHALL.
